UNITED STATES PATENT OFFICE

2,061,731

WHEEL FLANGE OILER

Perry H. Hamilton, Baltimore, Md., assignor to
Maintenance Equipment Company, Chicago,
Ill., a corporation of Illinois

Original application March 17, 1928, Serial No.
262,452. Divided and this application November
30, 1928, Serial No. 322,891

16 Claims. (Cl. 184—3)

This invention relates to a wheel flange oiler, and more particularly to a device for projecting oil from a reservoir mounted adjacent the rail onto the flange of a car wheel and the side of the rail head. This application is a division of my co-pending application, Serial No. 262,452, filed March 17, 1928.

A receptacle or reservoir holding a quantity of oil is mounted adjacent that side of the rail at which the wheel flange travels. A pair of similar pump mechanisms are mounted in the reservoir at spaced intervals longitudinally of the rail. Each pump mechanism comprises a plunger positioned to be depressed by the wheel flange thereby projecting oil through a discharge passage leading to a point adjacent the rail head from which the oil is thrown onto the wheel flange. The two plungers will be successively but separately depressed as the wheel travels along the rail. An intermediately pivoted lever is connected at its ends with the respective pump plungers so that as one plunger is depressed the other plunger will be elevated.

Each pump mechanism comprises a cylindrical depression or well extending vertically downward from the bottom of the reservoir, and open at its upper end so that oil may flow thereinto from the reservoir. Each pump plunger is formed at its lower end with a piston adapted to slidably fit within the well and expel the oil therefrom through the discharge passage when the piston is lowered into the well. When the plunger is elevated, the piston will be raised entirely out of the well so that oil may flow in from the reservoir.

The principal object of this invention is to provide a wheel flange oiler such as briefly described hereinabove and as disclosed more in detail in the specifications which follow.

Another object is to provide an improved form of pumping mechanism for use in a wheel flange oiler.

Another object is to provide improved means for connecting a pair of similarly operating oil pump mechanisms so that the depression of one pump plunger will elevate the other pump plunger and vice versa.

Numerous other objects and advantages of this invention will be more apparent from the following detailed description of one approved form of the apparatus. In the accompanying drawing:

Fig. 1 is a plan view of the apparatus mounted

on the rail, a portion of the rail head being cut away to facilitate the disclosure.

Fig. 2 is a longitudinal vertical section taken substantially on the line 2—2 of Fig. 1. A portion of the reservoir is shown in side elevation. 5

Fig. 3 is a transverse vertical section taken substantially on the line 3—3 of Fig. 2.

The main body portion of the receptacle or reservoir 1 is in the form of an integral casting, shaped at its rear bottom and top edges to fit 10 between the head 2 and base flange 3 of the rail, and secured to the web 4 of the rail by means of bolts 5 passing through the end walls of the receptacle. The fixed bottom wall 6 of the reservoir is formed adjacent either end thereof with 15 a vertically extending cylindrical well 7, the open upper end of which being in direct communication with the reservoir so that oil may flow thereto as indicated at the left of Fig. 2 and in Fig. 3. A discharge passage 8 is formed in the rear 20 wall 9 of the reservoir, with its lower end 10 communicating with the bottom portion of well 7, and its upper discharge end 11 extending out through a lip or flange 12 formed on the back wall member 9 of the reservoir 1 which lip fits 25 against the side of the rail head 2 and serves as a lubricant distributing bar or plate.

The cover member 13 which is secured to the main casting by bolts or equivalent connections 14 is formed with vertical guide passages 15 30 which are coaxial with the respective wells or cylinders 7. A plunger 16 is guided for vertical movement in each of these guide passages 15. Each plunger 16 terminates at its lower end in an enlarged piston 17 adapted to fit slidably 35 within the well or cylinder 7 when the plunger is lowered (as shown at the right-hand end of Fig. 2) and adapted to be raised into the main chamber of the reservoir when the plunger is elevated (as shown at the left of Fig. 2 and in 40 Fig. 3).

A lever or rocker member 18 has a downwardly extending central portion 19 adapted to be fulcrumed within a depression 20 formed centrally of the bottom wall 6 of the reservoir. Each end 21 of the rocker member engages within a recess 22 formed in one of the plungers 16. It will be apparent from Fig. 2 that when one of the plungers 16 is depressed, the movement thus imparted to the rocker 18 will elevate the other plunger 16, and vice versa. 50

An adjustable head, here shown in the form of a screw plug 23, is mounted in the upper end of each plunger 16 to be engaged by the wheel flange 55

indicated at 24. If necessary, the rocker 18 may be adjusted vertically by placing shims beneath its fulcrum 19 in the depression 20.

When one of the plungers is elevated, as shown at the left of Fig. 2 and in Fig. 3, practically the entire upper end of the well 7 is open so that oil from the receptacle or reservoir may flow directly in and fill the cylindrical well. When the plunger is depressed by the passing wheel flange 24 engaging the head 23 of plunger 16, the piston 17 will pass down into the well 7 and expel the oil from the well to the discharge passage 8 and outlet spout 11. At the same time the plunger at the other end of the receptacle will be elevated so that its well will receive a new supply of oil from the reservoir. It will now be apparent that as the wheel passes along the rail the pump mechanisms will be successively operated to discharge their oil against the wheel flange, and each is again recharged as the next pump mechanism is operated.

The upper flange extension 12 of the reservoir, in which the outlet spouts 11 are positioned, serves not only to house and protect the channels 11 and deflect the wheel flange inwardly away from the rail so that the oil may be projected upwardly into contact with the throat of the car-wheel flange, but also serves as a wiper engaging the beveled face of the wheel flange 24 to spread the oil that has been discharged thereon.

It will be apparent that the improved pump mechanisms here shown as operating in tandem, could be used separately, each plunger being provided with a spring or similar means for returning the plunger to its elevated position after the car wheel has passed (as disclosed in the parent application Serial No. 262,452, hereinabove referred to).

I claim:

40 1. A wheel flange oiler comprising a reservoir for holding oil adapted to be mounted adjacent the rail, a pair of oil wells formed in the reservoir, a discharge passage leading from each well to a point adjacent the rail-head, a plunger operating in each well, and a rocker member having its intermediate portion fulcrumed on the bottom of the reservoir and its ends connected with the respective plungers.

50 2. A wheel flange oiler comprising a reservoir for holding oil adapted to be mounted adjacent the rail, there being a pair of vertically extending cylindrical oil wells formed in the bottom of the reservoir, a discharge passage leading from the lower portion of each well to a point adjacent the railhead, a plunger above each well guided for vertical movement in the top wall of the reservoir, the lower end of the plunger entering the well when the upper end thereof is depressed by a passing wheel, and a rocker member having its intermediate portion fulcrumed on the bottom of the reservoir intermediate the wells and its ends connected with the respective plungers.

60 3. A wheel flange oiler comprising a reservoir for holding oil adapted to be mounted adjacent the rail, there being a pair of vertically extending cylindrical oil wells formed in the bottom of the reservoir, a discharge passage leading from the lower portion of each well to a point adjacent the railhead, a plunger above each well guided for vertical movement in the top wall of the reservoir, there being a head on the upper end of each plunger positioned to be depressed by a passing car wheel, and a piston on the lower end of each 70 plunger adapted to substantially fit slidably with-

in the well, and a rocker member having its intermediate portion fulcrumed on the bottom of the reservoir intermediate the wells, and its ends pivotally connected with the respective plungers whereby as one piston is depressed into its well to 5 expel the oil through the discharge passage, the other piston will be elevated out of the well to permit oil to flow into the well from the reservoir.

4. A wheel flange lubricator comprising a reservoir, means actuated by a car wheel for forcing lubricant from the reservoir, a wiper flange positioned adjacent the side of the rail head extending longitudinally thereof and adapted to engage the inner surface of a wheel flange, there being an outlet formed in the flange through which the lubricant is discharged.

5. A wheel flange lubricator comprising a reservoir, means actuated by a car wheel for forcing lubricant from the reservoir, a wiper flange positioned adjacent the side of the rail head extending longitudinally thereof and adapted to engage the inner surface of a wheel flange, there being a plurality of outlets in the flange spaced longitudinally thereof through which the lubricant is discharged.

6. A wheel flange lubricator comprising a reservoir, a plurality of mechanisms spaced longitudinally of a rail for separately forcing lubricant from the reservoir, a wiper flange positioned adjacent the side of the rail head and extending longitudinally of the rail past the mechanisms and adapted to engage the inner surface of a wheel flange, there being separate lubricant discharge outlets in the flange, one for each of the mechanisms.

7. In combination with a lubricant pumping mechanism for forcing lubricant to the rail head and car wheel flange, a wiper plate positioned at the side of the rail head and extending longitudinally thereof and adapted to engage the inner surface of the car wheel flange.

8. In combination with a lubricant pumping mechanism for forcing lubricant to the rail head and car wheel flange, a wiper plate positioned at the side of the rail head and extending longitudinally thereof and adapted to engage the inner surface of the car wheel flange, there being conduits in the plate having outlets through which the lubricant is discharged.

9. Track lubricating apparatus comprising in combination with the rails of a track and means to intermittently supply lubricant for lubricating one of the rails, a member rigidly attached to the inner edge of one of the track rails and projecting inwardly therefrom in position to be engaged by the flanges of passing car wheels and to deflect them inwardly, said projecting member being provided with a channel protected from the action of the car wheel flanges and through which lubricant is adapted to be fed upwardly into position to contact with the throat of the car wheel flanges as they pass over said projecting member.

10. Track lubricating apparatus comprising in combination with the rails of a track and means to supply lubricant for lubricating one of the rails, a member rigidly attached to the inner edge of one of the track rails and projecting inwardly therefrom in position to engage the flanges of passing car wheels and space the car wheel flanges so engaged away from the edge of the rail, and a lubricant discharge conduit passing upwardly through said projecting member and adapted to feed lubricant into position to con- 75

tact with the throat of the car wheel flanges as they pass said projecting member.

11. Track lubricating apparatus comprising in combination with the rails of a track and means to supply lubricant for lubricating one of the rails, a member rigidly attached to the rail and projecting inwardly from the inner edge of one of said rails in position to engage the flanges of passing car wheels and space the car wheel flanges so engaged away from the edge of the rail, and a lubricant discharge port in the upper face of said projecting member adapted to discharge lubricant in position to contact with the throat of the car wheel flanges as they pass said projecting member.

12. In a track oiling device, a plate having upwardly extending openings for the passage of oil to the head of the rail, means for securing said plate to said rail whereby to position the upper edge portion of said plate against the ball portion of the rail and to offset the rail from the wheel flange, and means operated by passage of a car over the rail for forcibly delivering oil to said openings.

13. In a track oiling device, a plate having upwardly extending openings for the passage of oil to the head of the rail, means for securing said plate to said rail whereby to position the upper edge portion of said plate against the ball portion of the rail and to offset the rail from the wheel flange, a supply tank, a pump for delivering oil from the supply tank to said openings,

and means operated by the passage of a car over the rail for operating said pump.

14. In a rail lubricating device of the class described, a lubricant distributor positioned at one side of the rail and comprising a lubricant distributing bar secured in position against a side face of the rail head and having a plurality of lubricant ducts extending to the upper edge of the bar, and means for supplying lubricant to said lubricant ducts.

15. In a rail lubricating device of the character described, a lubricant distributor including a lubricant distributing bar positioned along the side face of the rail head so that a portion of the inner face of said bar extends in substantially the same plane as the said side face of the rail head, there being a plurality of lubricant ducts spaced from each other longitudinally of said bar and having outlet openings at the side of the rail head, and means for supplying lubricant to said ducts.

16. In a rail lubricating device of the class described, a lubricant distributor positioned along a rail at the inner side face of the rail head, said member including a lubricant distributing bar provided with a plurality of lubricant ducts for discharging lubricant at the side of the rail head and means for supporting said bar so that a portion of its inner face extends substantially in the plane of the side face of the rail head.
